GOTTLOB HONOLD, OF STUTTGART, GERMANY, ASSIGNOR TO THE FIRM OF ROBERT BOSCH, OF STUTTGART, GERMANY.

ARMATURE FOR MAGNETO-INDUCTION MACHINES.

1,072,120.

Specification of Letters Patent.

Patented Sept. 2, 1913.

Application filed October 4, 1909. Serial No. 520,931.

To all whom it may concern:

Be it known that I, GOTTLÖB HONOLD, a subject of the German Emperor, residing at 11-13 Hoppenlaustrasse, Stuttgart, Germany, have invented certain new and useful Improvements in Armatures for Magneto-Induction Machines; and I do hereby declare the following to be a full, clear, and exact description of the invention, such as 10 will enable others skilled in the art to which it appertains to make and use the same.

This invention relates to the construction of armatures or bobbins for magneto induction machines of the type usually known 15 as "magnetos." In such machines, as usually constructed, the armature or bobbin is made up of a body portion carrying the winding in which electromotive force is induced, and two head pieces or pole pieces 20 of magnetic material such as iron or steel, which twice in each revolution bridge across the space between the magnet faces and divert the lines of force from the path through the body of the bobbin and through the 25 winding carried thereby. It is customary to support these bobbins, for rotation in the field, by means of two axle pins extending symmetrically from the body portion of the bobbin and suitably journaled in the frame 30 of the machine. With such construction it is impossible to slip on to the body or coil-carrying portion of the bobbin, a previously wound coil, and when the winding is wound on to the bobbin by hand or in a lathe the 35 winding must be so applied as to avoid the axle pins.

In accordance with the present invention it becomes possible to wind the coils on suitable forms and put them on the bobbins 40 after they are wound, or to wind the coil directly on the bobbin by hand or by means of a lathe without interference from the axle pins, so that the construction of the bobbins is simplified and improved. This 45 result is accomplished by connecting the axle pins to some part other than the coil-carrying portion of the bobbin, as, the pole pieces or extensions thereof, which pole pieces and extensions form the head-pieces. At the 50 same time the construction is such that this result is effected without necessitating any modification of the ordinary form of field-magnet frame and without materially reducing the area of the magnetic path 55 through the bobbin.

In the accompanying drawings Figures 1, 3, 5 and 6 are side views of bobbins constructed in accordance with the present invention, and Figs. 2 and 4 are end views of the bobbins and adjacent pole pieces.

In each figure *a* is the body or coil carrying portion of the bobbin, *b* and *c* are the head pieces, and *d* and *e* are the axle pins. In the construction shown in Figs. 1 and 2 the head pieces are flattened, the usual double T form being discarded. When the bobbins are constructed in this manner their manufacture is facilitated because the bobbin and the axle pins can be forged or pressed from a single piece of malleable iron. In the construction shown in Figs. 3 and 4 the head pieces have flanges *b*₁, *b*₂, *c*₁, *c*₂ so that the usual double T form is retained. The bobbins shown in Figs. 1, 2, 3 and 4, have a body or coil-carrying 75 portion with its axis inclined to the axis of the axle pins, to such a degree that by mounting the bobbin in a lathe on the axis *f* the winding may be applied directly to the body of the bobbin without interference from the axle pins. This facilitates the original construction of the armature, and also facilitates its repair.

In the modifications shown in Figs. 5 and 6 the head pieces *b* and *c* carry the axle 85 pins *d* and *e* at one extremity, and at the other extremity merge into the body portion without any overhang, so that the previously wound coil may be slipped into place as shown. In this case it is preferable to 90 curve the coil-carrying part of the bobbin as indicated in these figures.

It will be observed that in all figures the axis of the coil carrying body portion is angularly disposed with respect to the 95 axis of rotation, *i. e.*, the axis of the axle pins. The result is that the coil may be wound or slipped upon the coil carrying portion without encountering the axle pins, and yet, by reason of the angular relation 100 of the axis of the body portion with respect to the axis of the axle pins, the body portion lies directly in the magnetic path from one pole-piece of the magnetic frame to the other, and the head pieces fill the gap between the body portion and the faces of the 105 pole-pieces of the magnet frame, so that the magnetic path is substantially the same as in the ordinary form of double-T bobbin. In Figs. 1 and 3 the inclination of the axis 110

of the body portion is such as to make possible the winding of the coil in a lathe, while in Figs. 5 and 6, in which the construction is such as to permit the slipping on of a previously wound coil, the inclination and relative arrangement of the head pieces does not permit winding on a lathe, but where the axis of the body portion is at right angles to the axis of rotation, as in Fig. 6, the best magnetic path is secured.

Although, as has been pointed out, the armatures (including the axle pins) may, in some cases, be forged or pressed, or otherwise formed, from a single piece of metal, yet that is not essential to the invention, which may be embodied in armatures made up of assembled parts, as will readily be understood.

If the armature is to be oscillated, in the usual manner, by means of a cam and blade springs, then the cam may be cut directly upon the bobbin itself, as indicated at *k* in Figs. 1 and 3.

The modifications shown in Figs. 5 and 6, of the drawings form the subject-matter of a divisional application Serial No. 654694, filed October 14, 1911.

Having thus described my invention what I claim is:

1. A bobbin for magneto induction machines having head-pieces of magnetic material, a coil-carrying body portion connecting the head-pieces, the axis of the body portion being angularly disposed with respect to the axis of the axle pins, and axle pins extending from the head-pieces; substantially as described.

2. A bobbin for magneto induction machines having head-pieces of magnetic material, a coil-carrying body portion connecting the head-pieces, a coil mounted on said body portion and axle pins extending from the head-pieces, the body portion having its axis so angularly disposed with respect to the axis of the axle pins that the axle pins do not interfere with the operation of winding said coil; substantially as described.

3. A bobbin for magneto induction machines comprising a coil-carrying body-portion, flanged head-pieces of magnetic material extending from the body-portion, and axle pins extending from the head-pieces, the axis of the body-portion being angularly disposed with respect to the axis of the axle pins; substantially as described. 55

4. A bobbin for magneto induction machines having head-pieces, a coil-carrying body portion connecting the head-pieces, and axle pins extending from the head-pieces, one of said head-pieces having a portion 60 with flattened surfaces adapted to coöperate with blade springs; substantially as described.

5. A bobbin for magneto induction machines having head-pieces of magnetic material, a coil-carrying body portion connecting the head-pieces, a coil mounted on the body portion, and axle pins extending from the head-pieces, said head-pieces extending over said coil; substantially as described. 70

6. A bobbin for magneto induction machines having head-pieces of magnetic material, a coil carrying body portion connecting the head-pieces, a coil mounted on the body portion, and axle pins extending from the head-pieces, both ends of each of said head-pieces extending over said coil; substantially as described. 75

7. A bobbin for magneto induction machines having head-pieces, a coil-carrying body portion connecting the head pieces, a coil mounted on the body portion, and axle pins extending from the head-pieces in a direction inclined to the axis of the body portion, both ends of each of said head pieces extending over said coil; substantially as described. 85

In testimony whereof I have affixed my signature, in presence of two witnesses.

GOTTLOB HONOLD.
